UNITED STATES PATENT OFFICE

GROSVENOR D. MARCY, OF NEWTON HIGHLANDS, MASSACHUSETTS, ASSIGNOR TO GIL-
LETTE SAFETY RAZOR COMPANY, OF BOSTON, MASSACHUSETTS, A CORPORATION OF
DELAWARE

SAFETY RAZOR

Application filed August 17, 1929. Serial No. 386,559.

This invention relates to safety razors of the type wherein a thin flexible blade is clamped and positioned for shaving between two blade-shaping members.

5 My invention is particularly concerned with the problem of providing connecting means for the blade-shaping members which may be operated conveniently and rapidly to clamp them in operative position and as 10 readily for disengaging them when it is desired to clean the razor or replace the blade. Threaded connections have been used heretofore with satisfaction in respect to clamping efficiency and reliability. I contemplate 15 a connection which will possess these same advantages, but in addition thereto will be capable of more rapid engagement and disengagement, with the result that the shaver may save time both in the operation of assembling his razor and of disassembling or 20 taking it down.

In the type of razor wherein the holder comprises a cap, guard, and handle, my invention may be embodied by providing a 25 hook connection between the handle of the cap, such that the guard is interposed between the two and forced into blade-shaping position with respect to the cap by the movement of positioning the handle. This construction permits the use of efficient cam surfaces for effecting the clamping engagement. Moreover the same pressure which effects the 30 blade-shaping operation is effective to maintain the handle in its operative position. Similarly the single movement of the handle into disengaging position releases the clamp and guard so that they may be immediately 35 separated to disengage the blade.

I prefer to utilize a cross pin in the construction of the hook connection and to provide the blade with an aperture through which the cross pin may be passed in assembling the razor. An advantage incident to the construction is that the blade may be 40 located between the blade-shaping members

by a tongue having an elongated contour similar to the cross pin and thus is obviated the necessity for separate blade locating studs. So far as I am aware it is broadly new to utilize an elongated opening in the 50 blade for the purpose of accommodating an element of the connecting means and also for the purpose of locating the blade in the assembled razor.

These and other features of the invention 55 will be best understood and appreciated from the following description of a preferred embodiment thereof, selected for purposes of illustration and shown in the accompanying drawings, in which—

Fig. 1 is a view in perspective of the parts 60 of the razor separated from each other but arranged in order for assembling.

Fig. 2 is a view in side elevation showing 65 the razor handle in position for disengagement.

Fig. 3 is a view in side elevation showing 70 the assembled razor, and

Fig. 4 is a view in perspective of the assembled razor with the handle in telescoped 75 condition.

In the razor herein shown the blade-shaping members comprise a cap 10 and a guard 24. The cap 10 is provided with a convex outer face and with an inner concave blade-shaping face. A post or stud 12 of rectangular cross section extends upwardly from the blade-shaping face of the cap. At its upper end it is rounded and provided with a cross-pin 16 which projects symmetrically from opposite faces of the stud 12. An elongated rib 14 projects through the stud 12 upon the blade-shaping face of the cap 10, this corresponding substantially in contour with the cross-pin 16, being of substantially equal 80 length and width and rounded on its upper surface to facilitate positioning of the blade.

The cap 24 is provided with a lower blade-shaping face and with the guard teeth 25 along its longitudinal edges. It is provided 85

with a central aperture shaped to receive the stud 12 and cross pin 16 of the cap, that is to say it has a wide central rectangular portion 28, corresponding to the cross section of the stud 12, and an elongated slot 26 intersecting the portion 28 and corresponding in dimensions to the contour of the cross-pins.

The blade 18 is of thin flexible steel sharpened at both edges and provided with a central aperture corresponding in shape to that of the guard member and to the contour of the stud and tongue of the cap member. The aperture accordingly comprises a wide central portion 20 of rectangular outline and an elongated slot 22 corresponding in length and width to the cross pin 16 and rib 14.

The handle comprises a solid portion 30 and a hollow telescopic portion 38. As herein shown the handle is square in cross section but this is a matter of design and of secondary importance only. The solid portion is provided at its upper end with a tapering enlargement 36 which cooperates with a correspondingly contracting lower end of the hollow portions 38 preventing separation of the two and holding them frictionally in expanded condition when so positioned by the user.

The lower end of the portion 30 of the handle is slotted longitudinally forming spaced arms or branches 34 arranged to embrace the opposite faces of the stud 12 and cutaway in one face so as to form hooks with openings corresponding substantially in width to the diameter of the crosspin 16. Each arm 34 of the handle is provided with a transverse rib 32 inclined slightly downwardly and rearwardly with respect to the hook openings as shown in Fig. 3. The bottom surface of each rib 32 merges into the bottom surface of its associated arm 34 and, being slightly rounded eccentrically with respect to the center of the hook opening, acts as a cam surface to force the guard 24 downwardly when the handle is swung into an upright position. The end or bottom face of the handle is square and substantially perpendicular to the axis of the handle and the front face of the handle below the hook opening is also flat but is disposed at a slight inclination to the axis of the handle.

In assembling the illustrated razor the blade 18 is first placed upon the cap 10, being located thereon by the action of the rectangular stud 12 and the rib 14 in the aperture in the blade. It will be seen that the aperture in the blade not only permits the passage of the cross pin 16 but cooperates with the rib 14 beneath it in determining the shaving position of the blade. The guard member 24 is then positioned above the blade, being similarly located by the stud. The handle is then hooked upon the cross pin 16 in an inclined position as shown in Fig. 2 with its inclined front face in contact with the

guard. When it is desired to clamp parts of the razor in condition for shaving the handle is swung in a clock-wise direction from the position shown in Fig. 2 to that shown in Fig. 3. In this movement the cam surfaces formed by the sides of the hook act to depress the guard 24 against the yielding resistance of the blade 18, until the corner of the handle has passed from beneath the crosspin 16 and the handle reached its upright position. In effect this movement of the handle forces the guard and cap together by relatively moving the guard and cross pin to such position that the blade is fully shaped between the cap and guard. The handle is maintained with considerable rigidity in its upright position with its flat end surface in engagement with the flat upper face of the guard 24 and with the cross pin 16 resting upon the inclined upper faces of the ribs 32. The razor is now ready for use and may be employed with the handle in elongated position as shown in Fig. 3 or with it in telescopic position as shown in Fig. 4 in accordance with the preference of the user.

When it is desired to separate parts of the razor the handle is forcibly returned to its inclined position, there being sufficient resiliency in the parts to permit the slight contracting movement of the cap and guard necessary to permit this movement of the handle. The handle is now free to be detached by moving it to carry the cross pin 16 out of the hook, whereupon the guard may be lifted and the blade 18 exposed.

Having thus described my invention what I claim as new and desire to secure by Letters Patent is:—

1. A safety razor having blade shaping members, a stud projecting from one member through the other and having a cross pin, and a quick-detachable handle having square ended spaced hooks shaped to embrace the stud and engage both the cross pin and the face of the adjacent blade-shaping member and movable with a camming action to clamp said blade shaping members together in reaching a position of stability.

2. A safety razor having blade shaping members, one having a stud with a cross pin and rib beneath the cross pin, and the other having an aperture for this stud and a slot for the passage of the cross pin, and an interposed blade having a locating slot shaped to fit the rib of the blade-shaping member first mentioned and to permit the blade to be passed over the cross pin of the stud.

3. A safety razor having blade-shaping members, one having a stud with a cross pin and a rib on its face beneath the cross pin and parallel thereto, the other member being apertured for the stud and pin, an interposed blade having a locating slot shaped to permit the blade to be passed over the cross pin and to be located by the rib, and a handle ar-

ranged to be connected to the cross pin and acting to secure the blade-shaping members together.

4. In a safety razor, a cap having a concave blade-shaping face, a centrally disposed post projecting from said cap and having a longitudinally disposed rib at its foot, and a cross pin extending in parallel relation to the rib and at least as long as the rib.

10 Signed at Boston, Massachusetts, this fifteenth day of August, 1929.
GROSVENOR D. MARCY.
